UNITED STATES PATENT OFFICE.

JOHN WILLIAM HALL, OF LONDON, ENGLAND.

INTERNAL-COMBUSTION ENGINE.

1,187,829.

Specification of Letters Patent. Patented June 20, 1916.

Application filed March 25, 1913. Serial No. 756,634.

To all whom it may concern:

Be it known that I, JOHN WILLIAM HALL, a subject of the King of England, residing at Brixton Hill, London, England, have invented certain new and useful Improvements in Internal-Combustion Engines, of which the following is a specification.

This invention relates to improvements in internal combustion engines and has particular reference to an apparatus for supplying fuel to the engine-cylinder or combustion chamber.

By means of the present invention it is possible to employ heavy hydrocarbons, such as paraffin, although it is equally applicable for use with other liquid hydrocarbons, such as petrol or motor-spirit commonly employed in such engines. The invention may also be employed with gaseous fuel.

20 The type of fuel feeding device to which the present invention relates is characterized by a fuel displacer combined with a spring so proportioned as to enable the pressure of the air or other gas in the engine-cylinder, when led to one operating-face of the displacer, to move that displacer to different positions against the resistance of the spring; the purpose of this combination is to effect by another face a displacement into 25 the cylinder of different charges of fuel intended to be proportioned to the different pressures of air or other gas in the cylinder at the times when they operate the displacer. The weight of air or other gas in the cylinder varies directly, or approximately so, with the pressure, and therefore the movement of the displacer will vary very nearly directly as the weight of air present, so that the charge of fuel supplied to the engine 30 cylinder is measured and has its quantity determined by the quantity of air in the engine cylinder, as determined by its pressure, so that a substantially perfect combustible mixture of fuel and air is thus obtained.

In a fuel feeding device such as above described the present invention comprises, according to one embodiment, the combination with a casing of a fuel displacer which is a 35 sliding fit therein and is a differential or other piston device characterized by oper-

ating-faces which are entirely inflexible. Preferably there is also provided a timing device for the displacer. Thus a fuel feeder is obtained in which the displacer can have a 55 great range of motion and can be operated with precision throughout that range, to measure at different times different quantities of fuel in proportion to the weight of air or other combustion-supporting gas in 60 the engine-cylinder.

According to a modified construction the fuel-feeding device comprises a differential or other piston having its operating-faces entirely inflexible and chambers to contain 65 fluid packing for that piston. Preferably there are three chambers, one of them being a fuel chamber intermediate of the other two.

According to a further modification the 70 apparatus is so constructed that the displacement of the fuel is effected during the return (as distinguished from the primary) stroke of the displacer in order that the rate of delivery of fuel may be regulated independently of the rate of the primary impulsion of the displacer.

With any of the constructions above described there may be combined means for varying the speed of the return or delivery 80 stroke of the displacer in relation to the speed of its primary stroke.

Other features of the invention will be more clearly understood from the following description taken in connection with the accompanying drawings which illustrate preferred embodiments of the invention and in which—

Figure 1 is a section through the engine-cylinder and a portion of the apparatus comprising one modification of the invention; Fig. 2 is a side elevation from the right of Fig. 1; Fig. 3 is a plan view of Fig. 1, part in section; Fig. 4 is a part sectional view of the regulating device for the apparatus 90 illustrated in Figs. 1, 2 and 3; Fig. 5 is a sectional view of a modified construction of apparatus embodying the invention; Fig. 6 is a section on the line 6—6 of Fig. 5 looking in the direction of the arrows; Fig. 7 is a 100 sectional elevation of a modified form of regulating device, Fig. 8 shows a further

modified construction of fuel feeding device with means to adjust the yield of the controlling spring, Fig. 9 is a diagrammatic illustration of a modified mounting of the spring controlling the pump regulator piston; and Fig. 10 is a diagrammatic representation of a modified construction of controlling spring.

Referring to Figs. 1 to 4 it will be seen that in connection with the mixing chamber is a jet A by which the fuel is injected and this jet may be so disposed in its relation to the ignition device B that when the fuel is injected it will impinge upon the device and in this particular embodiment in line with the spark causing the ignition. A conduit A¹ for the supply of fuel is in connection with the fuel jet A but is opened or closed by a form of lift valve C controlled by a spring C¹ whose load or tension is adjustable as by means of the nuts C² on a screwed part of the valve-spindle. The valve is preferably of the spherical type having a projecting spindle C³ connected to the controlling spring, which normally maintains the valve in a position to close the conduit A¹ to the jet A.

In connection with the conduit A¹ there are preferably connected two other conduits A² each of which is in communication with the barrel or cylinder A³ (see Fig. 3) of a fuel pump. The pumps are preferably of the type in which the plunger A⁴ works in a cylinder of considerably greater volume than the volume of that portion of the plunger working in it. Both plungers A⁴ are connected by a yoke A⁵ and the latter is connected, centrally of the two plungers, by means of a rod D with a piston D¹ working in a cylinder D², said piston and cylinder being hereinafter referred to as a whole as the pump-regulator. The yoke is controlled in its movement by means of an adjustable spring D³. The plungers A⁴ and the piston D¹ each has operating-faces which are entirely inflexible.

The pump-barrels or cylinders A³ are in connection with the fuel supply reservoir by means of the conduit A⁶, the fuel being controlled in its admission to the pump-barrels or conduits in connection with them through a non-return valve or valves A⁷.

In connection with the pump-regulator cylinder D² between the head of the cylinder and the piston-head, is a conduit D⁴ connected at its other end with the engine-cylinder B¹ and opening therein at a point near the head of the cylinder so that it will be closed by the piston B² before the latter completes the end of its compression stroke. In this conduit is a timing device E, shown in section in Fig. 4, which will permit the gas undergoing compression in the engine-cylinder to communicate its pressure to the pump-regulator, but prior to ignition and

during expansion of the ignited gases, the device will close communication by the valve E¹ between the engine-cylinder and pump-cylinder D². The timing device also includes another valve E² in communication with that portion of the conduit D⁴ leading to the pump-regulator cylinder which, at the moment of firing, will release the pressure in the pump-regulator to permit fuel to be supplied to the fuel jet valve in the manner to be more particularly described hereinafter.

The two valves in the timing device for the pump-regulator may be similar to the valve described in connection with the fuel jet and they may be controlled in their movement by a lever E³ connected to them in such a manner that when an armature E⁴ rigidly secured to it is operated electro-magnetically at the time of firing or just prior thereto by the solenoid E⁵, the valve E¹ closing the conduit between the engine-cylinder and the pump-regulator will be closed and the other valve E² opened through the conduit E⁶ to the outside air.

In operation, the action of the apparatus is as follows:—Assuming that it is desired to utilize a heavy hydrocarbon as fuel it has been found that if a jet of a heavy hydrocarbon, such as paraffin, be played on to the spark gap of a spark plug, it will be ignited so that with the present apparatus as described above it is possible to utilize the paraffin in this manner as the jet has been arranged to spray on to the sparking device. Assuming that the piston in the engine-cylinder is about to commence its compression stroke, it will, during compression, cause a small quantity of the compressed gas, which in this case is air, to pass into the pump-regulator cylinder D² by means of the conduit D⁴ connecting the engine-cylinder and the regulator. The valve E¹ in the pump-regulator timing device is, during the compression stroke of the engine-piston, maintained open by means of the spring E⁷ acting on the armature E⁴ to permit this passage of the gas. The piston D¹ of the pump-regulator is consequently moved in its cylinder D² and in its travel withdraws the two pump-plungers A⁴ from their cylinders, thus causing an induction of fuel to the pump-barrels A³. During the movement of the piston D¹ its controlling spring D³ is becoming compressed. Near the end of its stroke the engine-piston closes the conduit D⁴ and it is obvious that this conduit will be closed at the same point in the stroke of the engine-piston every time. Therefore if the temperature remains constant, the pressure at that point in the stroke of the engine-piston will be a measure of the weight of air compressed therein and if the spring D³ be suitably adjusted, the induction of fuel to the pump-barrels or cylinders A³

will be regulated in accordance with the weight of air compressed in the engine-cylinder so that only sufficient fuel is supplied to be completely utilized in combustion.

- 5 When contact is made to cause a spark in the ignition device current is simultaneously passed through the coils of the electro-magnet E⁵ forming part of the timing device for the pump-regulator. When the electro-magnet 10 is thus energized its armature E⁴ is attracted to it and as hereinbefore explained, will close the valve E¹ controlling the conduit between the engine-cylinder and the pump-regulator and will open the valve E² 15 leading to the pump-regulator, opening it to the outside air. By thus opening this valve the regulator piston is moved under the action of its controlling spring so as to return the pump-plungers into their cylinders and 20 to force a quantity of fuel through the fuel jet. In all cases the pump-plungers A⁴ must be returned to a definitely ascertained point and outward movement, regulating the volume of fuel induced into the pump-barrels 25 A³, is regulated by the pressure in the engine-cylinder. The fuel passes into contact with the spark and is ignited thereby, or a portion of it is ignited thereby, and with the aid of the oxygen contained in the air 30 in the mixing chamber will be completely consumed and during its combustion will, in the well-known manner, force the piston in the engine-cylinder in its outward stroke due to the expansion caused by the combustion. 35 It will be obvious that the apparatus described is adjusted automatically in its supply of fuel to the engine-cylinder with the position of the spark in its relation to the stroke of the engine; that is to say, whether 40 the spark be retarded or advanced the injection of the fuel will only take place at the moment of sparking.

Owing to the advancing or retarding of the spark the ignition will not take place at 45 the same point in the stroke of the piston on all occasions, and the conduit between the engine-cylinder and the pump-regulator must be closed as by the valve E¹ (Fig. 4) or J² (Fig. 6) or by the engine-piston before 50 the completion of stroke of the engine-piston. If a fixed spark were employed the conduit could open into the top of the engine-cylinder or at any point above or beyond the limit of the stroke of the piston during 55 compression.

Preferably in connection with the conduit E⁶ from the timing device E which allows the pump-regulator to move under the action of its spring, there is employed a valve E⁸ 60 which may be controlled in any desired manner to regulate the rate at which the air is released from the cylinder of the pump-regulator. Thus, at high engine-speeds this valve may be fully opened, while at low 65 engine-speeds the air will be allowed to es-

cape at a slower rate, to allow for the variation in rate at which fuel is supplied to the mixing chamber. The valve may be regulated by hand, as illustrated, by means of the screwed spindle E⁹ or there may be lever-connections conveniently placed for control from the driver's seat.

A modified construction of apparatus for supplying fuel to the engine is illustrated in Figs. 5 and 6 in which the pump-regulator cylinder corresponding to D², and now shown at F, communicates at one end with a duct F¹ controlled as more particularly described hereinafter, and at the other end with a barrel F² in connection with a fuel supply and with the engine-cylinder. A piston composed of two portions F³ and F⁴, the operating faces of which are entirely fluxed, is so arranged that the portion F³ works in the cylinder F, while the portion F⁴ has provided for it a cylindrical guide F⁵. An extension F⁶ from the portion F⁴ has an enlargement F⁷ engaging one end of a coiled compression spring F⁸ located in a casing F⁹ forming an extension 90 of the cylindrical guide F⁵. The cylinder F, barrel F² and guide F⁵ are surrounded by a jacket F¹⁰ having a cover F¹¹ and the spaces N¹⁰, N¹¹ provided by the jacket and cover are adapted to be filled with oil preferably under pressure, which pressure may if desired be obtained by passing air under compression from any part of the passage F¹ through a non-return valve into the upper part of the oil chamber F¹⁰. Ducts F¹² 100 communicate between the oil-chamber and the cylinder F and guide F⁵ so that the oil will prevent fuel creeping into the cylinders F or F⁵ in the well-known manner.

In connection with the barrel F² is a cylindrical casing G having a conduit G¹ connecting it with the barrel F² and controlled by a ball-valve G² normally held in place by a spring G³. An inner cylindrical member G⁴ has ducts G⁵ through which the fuel may 110 flow from the duct G¹ when the ball-valve is raised. A conduit G⁶ connects the casing G with the engine-cylinder or with the induction pipe of the engine.

It is preferable when the fuel is not injected directly into the cylinder, to pump or force it, especially in the case of a heavy hydrocarbon, on to or through a wire gauze screen or the like either by means of spraying nozzles or otherwise. This screen may be disposed in any convenient portion of the fuel injecting device or it may be disposed in the induction pipe. In a similar manner a hollow cylindrical member H communicates by means of a conduit H¹ on the one hand with the fuel supply, and on the other hand with the interior of the barrel F² and is provided with a ball-valve H² controlled by a spring H³.

The timing or controlling device of cyl.

inder F is more particularly illustrated in Fig. 6 in which a valve J controls connection between a conduit J¹ leading to the interior of the cylinder and the conduit F¹, while a second valve J² controls communication between the conduit F¹ and the outside air which is opened to the conduit F¹ by the ducts J³. Stems J⁴ and J⁵ extend from the valve-heads J and J² respectively 10 and are operated by cams J⁶ and J⁷ respectively on a cam-shaft J⁸, preferably through the medium of rocking arms.

It will be clear that during the compression stroke in the engine-cylinder the cam 15 J⁶ operates the valve J to raise it from its seat and allow a small portion of the compressed gases to pass by means of the conduit J¹ through the conduit F¹ into the cylinder F, the valve J² meanwhile remaining 20 on its seat and closing communication between the outside air and the conduit F¹. Thus the piston F³ will be forced out of the cylinder F against the action of the spring F⁸ and according to the degree of compression 25 in the engine-cylinder so the piston will be forced to a greater or lesser extent out of the cylinder F. The barrel F² is assumed to be full of fuel and as the piston F⁴ is displaced and the piston F³ of larger diameter takes its place in the barrel F², fuel 30 will be forced through the conduit G¹, cylindrical member G and conduit G⁶ into the engine-cylinder or into the induction pipe, and the amount of fuel thus ejected will 35 be proportional to the extent to which the piston F³ is moved into the barrel F², that is to say, proportional to the pressure in the engine-cylinder. Before the mixture in the cylinder is fired the cam J⁶ is operated to 40 close the valve J and the valve J² is lifted by the cam J⁷ to allow the air to escape from the cylinder F thereby permitting the piston F³ to return by the action of the spring F⁸ to its initial position. Obviously as the 45 piston F³ returns to the cylinder F fuel will be drawn into the barrel F² through the conduit H¹ past the ball-valve H² owing to the inductive effect of the piston F⁴ of smaller diameter than the piston F³ taking 50 the place of the latter in the barrel F². Thus, assuming a four-stroke cycle there will be three-quarters of the cycle allotted to the return of the piston F³ to its normal position under the action of the spring F⁸ and 55 for the inflow of fuel to the barrel F², which is the reverse in action of the construction described in connection with Figs. 1-4. It may be, however, found desirable to alter the timing of the valves J and J² relatively 60 to the stroke of the piston in the engine-cylinder. For this purpose a differential connection such as K may be introduced between the driving shaft J⁹ and the cam shaft J⁸ so that the setting of the cam-shaft J⁸ 65 relatively to the shaft J⁹ may be altered by

moving the casing carrying the intermediate wheels of the differential connection.

A further modification of an electrically operated timing or controlling device to take the place of the device illustrated in Figs. 4 and 6 is illustrated in Fig. 7. A conduit L takes the place of the conduits D⁴ and J¹ and is connected at one end with the interior of the engine-cylinder, while at its other end it divides into two conduits L¹ and L², the former being controlled by a valve L³ and the latter opening into a chamber L⁴. The spindle L⁵ of the valve L⁴ moves in a cylindrical guide L⁶ and is maintained pressed down on its seating normally by the spring L⁷. Surrounding a portion of the guide L⁶ is a solenoid winding L⁸ to be energized in the manner explained hereinafter. The chamber L⁴ is formed by a hollow casing L⁹ integral with or connected 75 with the wall of the conduit L¹. In the casing L⁹ is a plug L¹⁰ resting on a seating L¹¹ having a hole centrally disposed in it for the reception of a valve-spindle L¹² connected with the valve L¹³. The duct controlled 80 by the valve L¹³ has opening into it other ducts L¹⁴ communicating with an annular space L¹⁵ registering with an orifice L¹⁶ in the casing L⁹. The plug L¹⁰ is held in place by a ring L¹⁷ in which is screwed another plug L¹⁸ having in it a conduit L¹⁹ connecting with the regulator pump barrel such as D² in Fig. 3 or F in Fig. 5. The plug also provides a seat or bearing surface for the spring L²⁰ which normally maintains the valve L¹³ in its place.

Assuming that the piston in the engine-cylinder is commencing its compression stroke, the solenoid L⁸ will be energized from a source of electrical energy controlled 105 by any convenient form of commutator and contacts and by its action it will raise the spindle L⁵ in the guide L⁶ and thus lift the valve L⁴ from its seating. The compressed gas then passes through the conduits L¹ and 110 L² and thus presses on the top of the valve L¹³ and on the base of the valve spindle L¹² with equal pressure provided that the surface areas of these two members are equal. Compressed gas is thereby admitted to the 115 duct L¹⁹ thence to the cylinder of the pump-regulator. At a given point in the compression stroke of the engine-piston, preferably before the completion of the stroke, the solenoid L⁸ is deenergized and the valve L³ 120 is reseated by the action of the spring L⁷. As the compression increases the compressed gas is still allowed to flow through the duct L² until finally the pressure in the chamber L⁴ is sufficient to overcome the pressure of the spring L²⁰ when the valve L¹³ is raised from its seat and the air is allowed 125 to escape from the cylinder of the pump-regulator through the conduit L¹⁹ and ducts L¹⁴, L¹⁶. This enables the piston in the 130

pump-regulator cylinder to be restored to its initial position.

There may be provided, in connection with the timing devices illustrated in Figs. 5 and 7, an adjustable air-leak such as E⁶ E⁸ E⁹ shown in Fig. 4. Thus it will be obvious that by suitably timing the apparatus all the controlling devices described may be arranged to deliver fuel either to the engine-cylinder during the compression stroke or to the induction pipe in front of the inlet valve to be drawn in on the subsequent induction stroke of the engine. This may take place past a spring loaded spraying valve 10 or a suitable cone nozzle may be used at the point of discharge of the fuel into the induction pipe.

In some cases it may be found desirable to introduce between the cylinder and the 20 controlling device such as E or its equivalent devices, a pressure chamber into which compressed gas is forced during the compression stroke and from which it is subsequently discharged into the pump-regulator cylinder after first closing the connection 25 between the engine-cylinder and that pressure chamber.

The modification illustrated in Fig. 9 will now be described. It may sometimes be desirable to vary the action of the spring controlling the pump regulator piston and for this purpose an adjustable sliding connection 30 may be inserted between the piston and the spring so that their relative positions 35 may be varied to modify the mechanical advantage of the pump-piston in overcoming the effort of the spring. This may be conveniently carried into effect by the employment of a link R pivoted at one end in a 40 support shown as a block R⁵ slidable between guides R⁶, and the position of which is controlled by the driver through suitable operating mechanism, such as a lever R³, while the other end of the link R engages 45 one end of the spring R⁴. The link R is slotted so that it may have a sliding engagement with a pin R¹ carried by the piston-rod R² of the pump-regulator to permit of its movement as a whole in a transverse direction only in relation to the axis of the piston-rod and is itself normally disposed transversely of the same axis. By movement of the support R⁵ carrying the link R the length of that portion of it between the 50 spring R⁴ and the connection of the link with the piston-rod at the pin R¹ may be altered to vary the leverage with which the spring acts to control the movement of the pump-regulator piston.

60 Fig. 8 illustrates a further modification of the invention having special reference to a method of adjusting the spring controlling the movement of the fuel displacer. In the cylinder M is a piston M¹ having in a recess 65 a block M² into which is screwed a plunger

M³ for the actual displacement of the fuel. Sliding on the plunger M³ is a flanged sleeve M⁴ providing a bearing surface for the spiral spring M⁵ and having holes M⁶ formed in its flange. The fuel chamber into 70 which the plunger M³ projects is shown at N and is in communication with the fuel supply through a conduit N¹ controlled by a spring-pressed non-return valve N². Fuel is ejected from the chamber N through a 75 conduit N³ controlled by a spring-pressed non-return valve N⁴. The valves N² and N⁴ may be of any convenient construction and preferably as illustrated, those shown being of a hollow sleeve type having outlet holes 80 at their upper ends adjacent the valve-body.

The device for admitting compressed gases from the engine-cylinder to the cylinder M comprises a casing O having a ported liner O¹ in which works a piston O² having a 85 reduced middle portion. The piston O² is operated, as in the case of the timing device illustrated in Fig. 6, from a shaft J⁸ having on it a cam O³ which actuates the piston O² through the medium of a pivoted lever O⁴. 90 The shaft J⁸ as shown in a similar connection in Fig. 6 may be provided with a differential mechanism such as K. A conduit O⁵ connects this admission device with the interior of the engine-cylinder as in the case 95 of the foregoing examples so that when the piston O² is in its uppermost position a port O⁶ in the liner O¹ is connected with another port O⁷ which is itself in connection with the end of the cylinder M. For this purpose the piston O² is raised against the action of the spring O⁸ and when it is desired to release the pressure of the air in the cylinder M, is allowed to drop back owing to the movement of the cam O³ and 100 the action of the spring O⁸ until it is in the position illustrated in which the port O⁷ is placed into communication with the port O⁹ open to the outside air.

The operation of the parts so far described will be the same in its main principles as in the construction illustrated in Figs. 5 and 6, that is to say, compressed gases from the engine-cylinder are led to the cylinder M whereupon the piston M¹ is forced out and the plunger M³ is introduced into the chamber N normally full of fuel to expel some of that fuel through the conduit N³ past the valve N⁴. On the return of the piston M¹ by the action of the spring M⁵, 115 the plunger M³ is withdrawn from the chamber N and fuel enters therein through the conduit N¹ past the valve N².

To adjust the yield of the spring M⁵ to suit required conditions a projection P extends from the casing of the chamber N and is threaded externally as illustrated, the pitch of the thread being either equal to the pitch of the spring coils or it may be slightly greater or less than that pitch as 125 130

found desirable. Working on the screw-thread thus formed is a correspondingly threaded sleeve P^1 , itself having an externally cut screw-thread which receives in that thread the coils of the spring as shown. Thus by rotating the member P^1 it is caused to travel along the projection P and to travel in the spring M^6 so that the effective length of the spring is thus adjusted. The end of the spring may be held rigid at one end in a notch P^{21} while the other end engages the flange of the sleeve M^4 hereinbefore referred to.

Sometimes it is preferable to allow a certain amount of slack between the end of the spring and its point of contact with the pump-regulator piston or a corresponding portion and if the spring is shortened by movement of the member P^1 the slack should also be proportionately lessened. This may be effected by making the thread on the member P of a greater pitch than that on the exterior of the member P^1 so that the spring, or a portion of it, is moved bodily in the direction of movement of the member P^1 .

To effect the movement of the member P^1 the latter may be provided with teeth P^2 engaging with the teeth of an elongated pinion P^3 mounted conveniently in a portion of the casing surrounding the spring as illustrated and having a drum P^4 about which is coiled, and to which is anchored, ends of Bowden wires P^5 . The other ends of the wires P^5 may be secured to any convenient lever device preferably working over an indicator dial so that by pulling on one and slackening on the other, the member P^4 P^3 is rotated to cause rotation of the member P^1 . This construction is only described in its broad elements and its details have not been specifically described but may be seen from the drawings, although attention is particularly called to the fact that the spring and the cylinder M are inclosed in a casing adapted as a container for oil which may flow to the piston O^2 through ducts O^{10} and O^{11} , opening into the cylinder O .

The invention is also applicable in cases where the fuel mixture is ignited by the heat of the engine-cylinder or by a high degree of compression, or both. It is obvious that according to the class of hydrocarbon employed the ignition may either take place comparatively slowly or in the form of an explosion.

If desired the fuel injector as a whole may be heated by waste heat from the exhaust gases or in any other manner.

In place of the spring and other controls described in connection with the inlet jet valve and the regulating device for the pump-regulator, positive operative connections could be employed for any or all of the parts between them and the crank-shaft

or other convenient moving portion of the engine.

Provision is preferably made for cutting off the supply of fuel if for any reason the ignition device stops or fails.

It may be found desirable to replace the spring such as D^8 or F^8 shown in the drawings as single springs, by duplex springs, such as illustrated in Fig. 10, wherein that portion S resisting the first movement of the piston is weak relatively to the resistance of the other portion S' so that with a highly attenuated charge in the cylinder, the resulting small compression may give the required movement to the fuel pump-plunger or its equivalent. This movement might otherwise not be given if the spring were of the single formation. Alternatively in place of springs it will be understood that, the pump-regulator piston can be so arranged as to compress a volume of gas with suitable modifications in the construction.

Many other modifications may be made in carrying the invention into effect provided always that the spirit of the invention is not departed from.

What I claim as my invention and desire to secure by Letters Patent is:—

1. A fuel feeding device for an internal combustion engine, such device comprising in combination, a casing, a fuel displacing piston sliding in the casing and having rigid operating faces, a conduit connecting one operating face of the displacer with the engine-cylinder to subject that face to the gas-pressure in the cylinder during compression, means to control the pressure in the casing, a spring operating on the displacer to exert a force in opposition to that of the pressure in the engine-cylinder and so proportioned that the said pressure is enabled to move that displacer to different positions against the resistance of the spring, fuel conduits connecting the said casing with a supply of fuel and with the fuel inlet to the engine-cylinder respectively and opening into that side of the casing containing the fuel delivery face of the piston-device, and controlling means for the said fuel conduits operated during movement of the displacer in one direction to permit fuel to be drawn through one of the conduits into the casing while during movement in the reverse direction the displacer discharges through another conduit a measured quantity of fuel into the engine-cylinder.

2. A fuel-feeding device for an internal combustion engine, such device comprising in combination, a casing, a fuel displacing piston sliding in the casing and having rigid operating faces, a conduit connecting one operating face of the displacer with the engine-cylinder to subject that face to the gas-pressure in the cylinder during com-

pression, a spring operating on the displacer to exert a force in opposition to that of the pressure in the engine-cylinder and so proportioned that the said pressure is enabled 5 to move that displacer to different positions against the resistance of the spring, fuel conduits connecting the said casing with a supply of fuel and with the fuel-inlet to the engine-cylinder respectively and opening 10 into that side of the casing containing the fuel-delivery face of the piston-device, means to control the pressure in the casing and comprising a multi-way valve device in the conduit which conducts pressure from the engine-cylinder to the piston-device said 15 valve having one way open to the outside air and means to control said valve-device which means is operated from a timing shaft to operate the valves in turn first to conduct pressure to the piston-device and subsequently to release that pressure.

3. A fuel-feeding device for an internal combustion engine, such device comprising in combination, a casing, a fuel displacing 20 piston sliding in the casing and having rigid operating faces, a conduit connecting one operating face of the displacer with the engine-cylinder to subject that face to the gas-pressure in the cylinder during compression, a spring operating on the displacer to exert a force in opposition to that of the pressure in the engine-cylinder and so proportioned that the said pressure is enabled 25 to move that displacer to different positions against the resistance of the spring, fuel conduits connecting the said casing with a supply of fuel and with the fuel-inlet to the engine-cylinder respectively and opening 30 into that side of the casing containing the fuel-delivery face of the piston-device, means to control the pressure in the casing and comprising a valve in the conduit which 35 conducts gas-pressure from the engine-cylinder to the casing, a conduit connecting the casing with the outside air and a valve controlling it and means to operate said valves 40 at required times for producing by variation of pressure in the casing an oscillation of the piston, a timing shaft to 45 operate said means.

4. A fuel-feeding device for an internal combustion engine, such device comprising in combination, a casing, a fuel displacing piston sliding in the casing and having rigid 50 operating faces, a conduit connecting one operating face of the displacer with the engine-cylinder to subject that face to the gas-pressure in the cylinder during compression, a spring operating on the displacer to 55 exert a force in opposition to that of the pressure in the engine-cylinder and so proportioned that the said pressure is enabled to move that displacer to different positions 60 against the resistance of the spring, fuel conduits connecting the said casing with a supply of fuel and with the fuel inlet to the engine-cylinder respectively and opening 65 into that side of the casing containing the

supply of fuel and with the fuel-inlet to the engine-cylinder respectively and opening into the casing to the fuel-delivery face of the piston-device, means to control the pressure in the casing and comprising a multi-way valve-device in the conduit which conducts pressure from the engine-cylinder to the piston-device said valve having one way open to the outside air, means to control said valve-device, which means is operated from 70 a timing shaft, and a differential mechanism forming a connection between the timing shaft and the controlling device to constitute an adjusting gear for the timing.

5. A fuel-feeding device for an internal combustion engine, such device comprising in combination, a casing, a fuel displacing piston sliding in the casing and having rigid operating faces, a conduit connecting one operating face of the displacer with the engine-cylinder to subject that face to the gas-pressure in the cylinder during compression, a spring operating on the displacer to exert a force in opposition to that of the pressure in the engine-cylinder and so proportioned that the said pressure is enabled to move that displacer to different positions against the resistance of the spring, fuel conduits connecting the said casing with a supply of fuel and with the fuel-inlet to the engine-cylinder respectively and opening 80 into that side of the casing containing the fuel-delivery face of the piston-device, means to control the pressure in the casing and comprising a valve in the conduit which 85 conducts gas-pressure from the engine-cylinder to the casing, a conduit connecting the casing with the outside air and a valve controlling it and means to operate said valves 90 at required times for producing by variation of pressure in the casing an oscillation of the piston, a timing shaft to operate said means, and a differential mechanism forming a connection between the timing shaft and the controlling device to constitute an 95 adjusting gear for the timing.

6. A fuel-feeding device for an internal combustion engine, such device comprising in combination, a casing, a fuel displacing piston sliding in the casing and having rigid 100 operating faces, a conduit connecting one operating face of the displacer with the engine-cylinder to subject that face to the gas-pressure in the cylinder during compression, means to control the pressure in the casing, a spring operating on the displacer to exert a force in opposition to that of the pressure in the engine-cylinder and so proportioned that the said pressure is enabled to move that displacer to different positions 105 against the resistance of the spring, fuel conduits connecting the said casing with a supply of fuel and with the fuel inlet to the engine-cylinder respectively and opening 110 into that side of the casing containing the

fuel-delivery face of the piston-device, controlling means for the said fuel conduits operated during movement of the displacer in one direction to permit fuel to be drawn 5 through one of the conduits into the casing while during movement in the reverse direction the displacer discharges through another conduit a measured quantity of fuel into the engine-cylinder, and a container for 10 fluid to form a fluid packing for the piston.

7. A fuel-feeding device for an internal combustion engine, such device comprising in combination, a casing, a fuel displacing 15 piston sliding in the casing and having rigid operating faces, a conduit connecting one operating face of the displacer with the engine-cylinder to subject that face to the gas-pressure in the cylinder during compression, means to control the pressure in the casing, a spring operating on the displacer to exert a force in opposition to that of the pressure in the engine-cylinder and so proportioned that the said pressure is enabled 20 to move that displacer to different positions against the resistance of the spring, fuel conduits connecting the said casing with a supply of fuel and with the fuel-inlet to the engine-cylinder respectively and opening 25 into that side of the casing containing the fuel-delivery face of the piston device, controlling means for the said fuel conduits operated during movement of the displacer in one direction to permit fuel to be drawn 30 through one of the conduits into the casing while during movement in the reverse direction the displacer discharges through another conduit a measured quantity of fuel into the engine-cylinder, and a container 35 surrounding the fuel-delivery end of the piston-device and adapted to contain fluid for packing that end of the device.

8. A fuel-feeding device for an internal combustion engine, such device comprising 45 in combination, a casing, a fuel displacing piston sliding in the casing and having rigid operating faces, a conduit connecting one operating face of the displacer with the engine-cylinder to subject that face to the gas-pressure in the cylinder during compression, a spring operating on the displacer to exert a force in opposition to that of the pressure in the engine-cylinder and so proportioned that the said pressure is enabled to move 50 that displacer to different positions against the resistance of the spring, fuel conduits connecting the said casing with a supply of fuel and with the fuel-inlet to the engine-cylinder respectively and opening into that 55 side of the casing containing the fuel-delivery face of the piston-device, means to control the pressure in the casing and comprising a multi-way valve-device in the conduit which conducts pressure from the en-

gine-cylinder to the piston-device said valve 65 having one way open to the outside air, means to control said valve-device and operated from a timing shaft to operate the valves in turn first to conduct pressure to the piston-device and subsequently to release 70 that pressure, and a fluid container surrounding the piston-device to form a fluid packing for the piston.

9. A fuel-feeding device for an internal combustion engine, such device comprising 75 in combination, a differential piston-device whose larger end is surrounded by a cylinder, a conduit connecting said cylinder with the engine-cylinder, a timing device, a timing shaft operating said device to alternately open the cylinder surrounding the piston-device to the engine-pressure and then to release the pressure therefrom, a fuel-chamber into which the smaller end of the piston is inserted during movement of the 85 piston-device in one direction, a conduit connecting the fuel-chamber with the supply of fuel and another conduit connecting the fuel-chamber with the engine-cylinder, valves controlling both of the said conduits 90 connected with the fuel-chamber, a spring operating on the piston-device to exert a force in opposition to the pressure in the engine-cylinder and a casing surrounding the piston-device and adapted to contain 95 fluid packing for the said piston-device.

10. A fuel-feeding device for an internal combustion engine, such device comprising 100 in combination, a differential piston-device whose larger end is surrounded by a cylinder, a conduit connecting said cylinder with the engine-cylinder, a timing device, a timing shaft operating said device to alternately open the cylinder surrounding the piston-device to the engine-pressure and then 105 to release the pressure therefrom, a fuel-chamber into which the smaller end of the piston is inserted during movement of the piston-device in one direction, a conduit connecting the fuel-chamber with the supply of fuel and another conduit connecting the fuel-chamber with the engine-cylinder, 110 valves controlling both of the said conduits connected with the fuel-chamber, a spiral spring operating on the piston-device to exert 115 a force in opposition to that of the pressure in the engine-cylinder, a support for the spring comprising an internally threaded nut having on its outer face helical grooves to engage some of the coils of the spring, 120 the outer raised surfaces of the nut having axial teeth thereon, an externally threaded support to engage the internal thread of the nut, an elongated pinion to engage the teeth on the external surfaces of the nut, and 125 means to revolve the pinion about its axis so that the nut may be moved in the spring to regulate the resistance thereof.

11. A fuel-feeding device for an internal combustion engine, such device comprising in combination, a differential piston-device whose larger end is surrounded by a cylinder, a conduit connecting said cylinder with the engine-cylinder, a timing device, a timing shaft operating said device to alternately open the cylinder surrounding the piston-device to the engine-pressure and then to release the pressure therefrom, a fuel-chamber into which the smaller end of the piston is inserted during movement of the piston-device in one direction, a conduit connecting the fuel-chamber with the supply of fuel and another conduit connecting the fuel-chamber with the engine-cylinder, valves controlling both of the said conduits connected with the fuel-chamber, a spiral spring operating on the piston-device to exert a force in opposition to that of the pressure in the engine-cylinder, a support for the spring comprising an internally threaded nut having on its outer face helical grooves to engage some of the coils of the spring, the outer raised surfaces of the nut having axial teeth thereon, an externally threaded support to engage the internal thread of the nut, an elongated pinion to engage the teeth on the external surfaces of the nut, the pinion being extended at one end to provide a drum whereon is coiled a wire by movements of the ends of which the pinion may be rotated.

12. A fuel-feeding device for an internal combustion engine, such device comprising in combination, a differential piston-device whose larger end is surrounded by a cylinder, a conduit connecting said cylinder with the engine-cylinder, a timing device, a timing shaft operating said device alternately to open the cylinder surrounding the piston-device to the engine-pressure and then to release the pressure therefrom, a fuel-chamber into which the smaller end of the piston is inserted during movement of the piston-device in one direction, a conduit connecting the fuel-chamber with the supply of fuel and another conduit connecting the fuel-chamber with the engine-cylinder, valves controlling both of the said conduits connected with the fuel-chamber, a spiral spring operating on the piston-device to exert a force in opposition to that of the pressure in the engine-cylinder, a support for the spring comprising an internally threaded nut having on its outer face helical grooves to engage some of the coils of the spring, the outer raised surfaces of the nut having axial teeth thereon, an externally threaded support to engage the internal thread of the nut, an elongated pinion to engage the teeth on the external surfaces of the nut, means to revolve the pinion about its axis so that the nut may be moved in

the spring to regulate the resistance thereof, 65 and a casing surrounding the piston-device, spring and pinion and a fluid packing contained in said casing.

13. A fuel-feeding device for an internal combustion engine, such device comprising, 70 in combination, a casing, a fuel displacing piston sliding in the casing having rigid operating faces, a conduit connecting one operating face of the displacer with the engine-cylinder to subject that face to the 75 gas-pressure in the engine-cylinder during compression, means to control the pressure in the casing, a spring operating on the displacer to exert a force in opposition to that of the pressure in the engine-cylinder and so 80 proportioned that the said pressure is enabled to move that displacer to different positions against the resistance of the spring, fuel conduits connecting the said casing with a supply of fuel and with the fuel inlet to 85 the engine-cylinder respectively and opening into that side of the casing containing the fuel-delivery face of the piston-device, controlling means for said fuel conduits operated during movement of the displacer in 90 one direction to permit fuel to be drawn through one of the conduits into the casing while during movement in the reverse direction the displacer discharges through another conduit a measured quantity of fuel 95 into the engine-cylinder, and means to regulate the action of the spring.

14. A fuel-feeding device for an internal combustion engine, such device comprising, 100 in combination, a casing, a fuel displacing piston sliding in the casing having rigid operating faces, a conduit connecting one operating face of the displacer with the engine-cylinder to subject that face to the gas-pressure in the engine-cylinder during compression, means to control the pressure in the casing, a spring operating on the displacer to exert a force in opposition to that of the pressure in the engine-cylinder and so 105 proportioned that the said pressure is enabled to move that displacer to different positions against the resistance of the spring, fuel conduits connecting the said casing with a supply of fuel and with the fuel inlet to 110 the engine-cylinder respectively and opening into that side of the casing containing the fuel-delivery face of the piston-device, controlling means for said fuel-conduits operated during movement of the displacer in one direction to permit fuel to be drawn 115 through one of the conduits into the casing while during movement in the reverse direction the displacer discharges through another conduit a measured quantity of fuel 120 into the engine-cylinder; and a device for adjusting the yield of the spring comprising an externally screw-threaded member adapted to receive in its threads the coils of the

spring, means to move the said screw-threaded member to any position in the spring-coils, and means to hold it stationary in its adjusted position.

- 5 15. A fuel-feeding device for an internal combustion engine, such device comprising, in combination, a casing, a fuel displacing piston sliding in the casing having rigid operating faces, a conduit connecting one operating face of the displacer with the engine-cylinder to subject that face to the gas-pressure in the engine-cylinder during compression, means to control the pressure in the casing, a spring operating on the displacer to exert a force in opposition to that of the pressure in the engine-cylinder and so proportioned that the said pressure is enabled to move that displacer to different positions against the resistance of the spring, fuel-conduits connecting the said casing with a supply of fuel and with the fuel-inlet to the engine-cylinder respectively and opening into that side of the casing containing the fuel-delivery face of the piston-device, controlling means for said fuel-conduits operated during movement of the displacer in one direction to permit fuel to be drawn through one of the conduits into the casing while during movement in the reverse direction the displacer discharges through another conduit a measured quantity of fuel into the engine-cylinder, means to adjust the yield of the spring comprising an internally threaded nut having on its outer face helical grooves to engage some of the coils of the spring, an externally threaded support for the nut, and means to revolve the nut to cause it to travel to a predetermined distance along the support.
- 30 16. Apparatus for the supply of liquid fuel to cylinders of internal combustion engines in proportion to the weight of air therein, such apparatus comprising piston chambers, rigid piston-members reciprocated in the piston chambers, a resilient device against the pressure of which such piston-members are moved in one direction by gas-pressure in one of the chambers derived from the engine-cylinder to positions varying with such gas-pressure and moved in the other direction by such resilient device, valves for controlling the supply of liquid fuel to and from another of such chambers, and pressure-retaining and releasing means for the chamber in which the gas-pressure operates to move the piston-member, substantially as described.
- 45 17. A fuel feeding device for an internal combustion engine, such device comprising a casing, a fuel displacer sliding in the casing and having rigid operating faces, and a spring for the fuel displacer so proportioned as to enable the pressure of gas in the en-

gine-cylinder, when led to one operating face of the displacer, to move the displacer 65 to different positions against the resistance of the spring according to the amount of such pressure.

5 18. In a fuel feeding device for an internal combustion engine, the combination of 70 a casing, a displacer sliding in the casing and having rigid operating faces, and a spring so proportioned as to enable the pressure of gas in the engine-cylinder, when led to one operating face of the displacer, to 75 move the displacer to different positions against resistance of the spring, a timing device for the fuel feeding device to admit compressed air to the latter and release it therefrom at required times. 80

15 19. A fuel feeding device, for an internal combustion engine, such device comprising a casing, a piston in the casing having its faces inflexible, chambers to contain fluid packing for the piston, and a spring so proportioned as to enable the pressure of gas in the engine-cylinder when led to one operating face of the piston to move the piston to different positions against the resistance of the spring according to the amount 90 of such pressure.

20 20. In a fuel feeding device for an internal combustion engine, the combination of a piston having rigid operating faces, the casing in which the piston slides, with a 95 spring so proportioned as to enable the pressure of gas in the engine-cylinder, when led to one operating face of the piston, to move the piston to different positions against the resistance of the spring, a timing device for 100 the fuel feeding device to admit air to the latter and release it therefrom at required times, and a differential gear for the timing device to constitute an adjusting gear for the timing. 105

25 21. In a fuel feeding device for an internal combustion engine, the combination of a casing, a piston sliding in the casing and having rigid operating faces, a spiral spring so proportioned as to enable the pressure of 110 gas in the engine-cylinder, when led to one operating face of the piston, to move the piston to different positions against the resistance of the spring, an externally screw-threaded member adapted to receive in its 115 thread the coils of the spring, means to move the said member to any position in the spring-coils to adjust the effective length of the spring, and means to hold the said member stationary in its adjusted position.

30 22. A fuel-feeding device for explosion engines comprising in combination, a piston-pump having a piston with inflexible operating faces, a connection between the 125 engine-cylinder and the pump-casing to

lead compressed air to one face of the piston, another connection between the source of fuel-supply and the pump-casing to conduct fuel to the other working face of the 5 piston, means controlling the opening and closing of the said conduits, and a spring pressing on the piston to oppose its movement under the pressure of air from the engine-cylinder and of such a strength that 10 the piston is moved to different positions in

the casing according to the pressure exerted by such air.

In testimony whereof I have signed my name to this specification in the presence of two subscribing witnesses.

JOHN WILLIAM HALL.
